2 SHEETS-SHEET 2.

UNITED STATES PATENT OFFICE.

GEORGE E. KNEPPER, OF ALTOONA, PENNSYLVANIA.

REFRIGERATOR-CAR.

1,080,983.

Specification of Letters Patent.

Patented Dec. 9, 1913.

Application filed November 11, 1912. Serial No. 730,673.

To all whom it may concern:

Be it known that I, GEORGE E. KNEPPER, a citizen of the United States, residing at Altoona, in the county of Blair and State 5 of Pennsylvania, have invented certain new and useful Improvements in Refrigerator-Cars, of which the following is a specification.

This invention relates to the subject of 10 refrigerator cars, and has for its primary object means for maintaining a greater or less degree of low temperature within the car, according to the nature of the contents thereof, through the medium of a plurality 15 of combined ice and brine tanks.

With this end in view the invention contemplates a refrigerating device which consists of a plurality of tanks preferably arranged in each end of the car, the said tanks 20 each being in communication with the other and having means associated therewith, whereby the height of brine can be regulated within the tanks. Accordingly, when the tanks are nearly full of brine the temperature 25 within the car will be considerably lower, than when the tanks are only half filled. This is a very important feature in a refrigerator car, inasmuch as the provision thereof facilitates the safe transportation of 30 a wide variety of products at the proper temperature not otherwise possible where a fixed degree of cold is furnished by the refrigerating means. In the transportation of some fruits, which are shipped before 35 they are ripe, it is desirable to have a temperature that will permit the fruit to ripen somewhat by the time it reaches its destination. In this case, the present invention is very useful, and also very economical be- 40 cause it only furnishes the required degree of frigidity, without the aid of warmer air from the outside, which is often injurious to the shipment within the car.

Another object of this invention is to pro- 45 vide ample air circulating space around the combined ice and brine tanks, to obtain the maximum cooling efficiency from the refrigerating means. In connection with the provision of increased air circulating space, 50 the present invention also provides means for keeping articles packed within the car away from the tank, and further provides means for draining from the car the precipita- 55 tion collecting on the exterior of the tanks, without the ingress of air.

With these and other objects in view which

will more readily appear as the description of the case proceeds, the same consists in the novel construction, combination and arrangement of parts hereinafter more fully 60 described, illustrated and claimed.

A preferred and practical embodiment of the invention is shown in the accompanying drawings, in which:

Figure 1 is a transverse sectional view of 65 the end of a car showing the invention applied to the car. Fig. 2 is a longitudinal section of a portion of a car, showing the invention in side elevation. Fig. 3 is a detail front view of the piping used to regulate the 70 height of brine in the tanks. Fig. 4 is a side elevation of the construction shown in Fig. 3. Figs. 5 and 6 are detail views of the drain plug used to drain the brine tank.

Like reference characters designate corresponding parts throughout the several figures of the drawings.

Referring specifically to the accompanying drawing C designates a car body with the present invention installed therein. In 80 carrying out the idea embodied in this application, it will be understood that the plurality of refrigerant tanks 1 may be placed at either one, or both ends of the interior of the car. The said refrigerant tanks are 85 filled with ice and salt which forms brine, and are mounted upon a supporting base 2 which elevates the tanks from the bottom of the car, and provides ample space for the circulation of air underneath the tanks. It 90 will also be noted that the tanks 1 are spaced away from the end of the car as indicated at 3, and are provided on the outside thereof with a plurality of current deflecting baffles 4 which prevent the air from keeping in close 95 contact with the tanks, thus deflecting it and causing it to intermingle with more or less warmer currents of air.

Among the many advantages in having a 100 plurality of ice and brine tanks 1, is, that the salt water contained therein is prevented to a greater degree from splashing over the tops thereof when the car is subjected to the usual shocks and jars, than would be the case if only one large tank were used. How- 105 ever, provision is made within each tank, to reduce the splashing out of the water to a minimum, by placing the guards 1^a on the interior thereof near the top. The said guards are similar in structure to the baffles 110 4 and extend all of the way around the sides of each tank.

2
In order to protect the tanks from coming in contact with articles stored within the car, there is provided a protecting wall 5 which is provided at the top and bottom thereof with the screen, 6. However, the bottom screen portion is made in sections 7 and hinged to the wall 5 as indicated at 8, which permits of the access to the drain plugs 9 at the bottom of each of the tanks 1. The tops of the tanks 1 are also provided with the screens 6^a which prevent ice which is put in through the hatch doors 10, from falling down into the space between the tanks and the car and also between the tanks and the walls 5.

10 The drain plugs 9, it will be observed, consist of an interiorly threaded collar 11 which is adapted to be riveted or otherwise secured to the tanks 1 near the bottom thereof. A threaded plug 12 which is provided with the opening 13 is screwed into the threaded collar 11. The head portion of the plug is provided with a square knob 14 which facilitates the unscrewing of the plug by means of a monkey wrench or key. 15 When it is desired to drain the tanks the plug is unscrewed far enough to permit the opening 13 to come on the outside of the tank, and water issuing therefrom will be directed downwardly toward the bottom of the car instead of out into the compartment where the products are stored.

20 In connection with draining the tanks it will be observed that the bottom of the car 35 C is provided with the upstanding bead 15 which tends to prevent water of condensation which drips from the tanks, and also the drain water, from spreading over the floor of the car. However, in order to provide for the carrying off of the said water 40 the bead 15 is provided with the openings 16 which are in communication with a gutter 16^a and the spouts 17 which lead to the bowls 18 of the traps 19. Each of the said traps 19 is secured to the bottom of the car 45 by the brackets 20 to which they are pivoted. Connected with the bowl of each trap and extending on the other side of the pivot is a weighted arm 21 which serves as a counter-balance to restore the bowl to its normal 50 position after it has been caused to empty by the weight of water therein. It will be observed in connection with the bowl 18 that the same will hold a sufficient amount 55 of water to cover the end of the spout 17, thus forming a water seal which prevents air from entering the car through the spout.

60 Each of the tanks 1 is provided with an outlet connection 22 which is in communication with a drain pipe line 23 that is common to all of the tanks, and located preferably near the middle portion thereof. Suitably located along the pipe line 23, and in communication therewith is a three-way 65 valve 24 which is provided with the lateral

70 pipe extensions 25 and 26. The extension 25 is connected, to a vertical pipe member 27 which extends upwardly from the middle portion of the tank to a position substantially opposite the splash guard 1^a on the interior of the tank. At this point there is a horizontal pipe member 28, in communication with the pipe member 27, and also in communication with a downwardly extending pipe member 29. The said pipe member 29 communicates with a T fitting 30 which in turn, is in communication with the pipe extension 26. The remaining outlet of the T fitting 30 is connected to an exhaust pipe 31 which extends downwardly 75 and empties into the trap 19 underneath the car.

80 The tanks 1 are steadied and additionally secured in the car body, by the cross-beams 32, which are provided with openings 32^a to permit the unobstructed passage and circulation of air around the tanks. The two uppermost cross-beams 32 have suitably secured thereto, the brackets 33 in which a valve operating rod 34 is rotatably mounted. The said rod 34 is provided with a handle 35, which is accessible through the hatch door 10. The end of the rod opposite the handle is connected to a link 36, which is in turn operatively connected with the 90 stem 24^a of the draw-off valve 24.

95 From the foregoing description, it will readily be seen that the plurality of tanks 1 are accessible for filling with ice and salt, through the hatch doors 10 on the top of the car, and when they are filled, and the brine forms it will rise, for example, in the tanks to a level corresponding to the height of the horizontal pipe 28. The valve 24 is normally turned so the brine will flow from the drain pipe line 23, through the valve, up the vertical pipe 27 and through the horizontal pipe 28, thence downwardly through the pipe 29 and its connections to one of the traps 19, where it is emptied. 100 Thus, the piping arrangement just referred to, and the valve in its normal position constitute an overflow or safety device, for the tanks. However, when it is desired to reduce the level of the brine, the valve 24 is given a quarter turn by moving the handle 35. The brine is then permitted to flow directly from the pipe line 23 through the valve 24, pipe extension 26, and T fitting 30 into the exhaust pipe 31, from whence 110 it is emptied at one of the traps 19.

115 The foregoing description shows how it is possible to reduce the brine to the level of the drain pipe line 23, but each of the tanks can be further emptied by its individual drain plug 9. The water thus drawn off being conducted to the traps 19 by the spouts 17.

120 It is thought that the many features and advantages of this invention will be read- 130

ily apparent, and that minor details of construction may be resorted to without sacrificing the spirit of the invention or departing from the scope of the claims.

5 It will be readily noticed that the provision which is here afforded for retaining the brine from one icing station to another is one of the principal objects of the invention, and the facilities thus afforded make it 10 quite possible to obviate the necessity of discharging brine on the road bed, or providing additional storage tanks in the car to suitably take care of the brine until the terminal points are reached.

15 I claim:

1. A refrigerator car having a plurality of refrigerant containing tanks, a supporting base therefor, air current deflecting baffles on the exterior of said tanks, splash guards on the interior of each tank, means associated therewith for regulating the volume of the refrigerating agent therein, and means for draining each individual tank.

2. A refrigerator car comprising in combination with a car body, a plurality of refrigerant containing tanks installed therein, cross-beams extending transversely of the car body and bracing the tanks, drain plugs located near the bottom of each tank, a drain pipe line in communication with each of said tanks, a valved device connected with said pipe line for regulating the volume of refrigerating agent within the tanks, and a valve operating mechanism secured to the said cross-beams, said mechanism comprising a valve operating rod, a handle pivoted thereto, and a link having operative connection with the said valve.

3. A refrigerator car comprising in com-

binatiion with a car body, a plurality of refrigerant containing tanks, drain plugs located near the bottom of each of said tanks, a drain pipe line common to all of the tanks and communicating therewith at the intermediate portions thereof, an angular outlet pipe in communication with the drain pipe, a valve interposed between the drain and outlet pipes, a liquid level elevating piping in fixed communication with one side of the valve, and also in fixed communication with the outlet pipe on the other side of the valve, and means for opening and closing said valve.

4. A refrigerator car comprising in combination with a car body, a plurality of refrigerant containing tanks, a supporting base therefor, drain plugs for each of said tanks, a bead provided with openings secured to the floor of the car body, the latter having a gutter adjacent the said bead, a water seal trap secured to the underside of the car body, a drain pipe line in communication with the intermediate portion of each of said tanks, an outlet pipe leading from the drain pipe to the said trap, a valved liquid level elevating device interposed between the drain and outlet pipes, a protecting element adjacent the piped sides of the tanks, and outlet means in communication with the gutter in the car body and the said water seal trap.

In testimony whereof I hereunto affix my signature in the presence of two witnesses.

GEORGE E. KNEPPER.
